(57) **CLAIM**

The ornamental design for a repeater for wireless communications, as shown and described.

DESCRIPTION

FIG. 1 is a front perspective view of a repeater for wireless communications showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is rear perspective view thereof; and,

FIG. 9 is another front view thereof in an environment of use.

The unshaded bottom surface shown between the broken line and solid line in FIG. 7 forms no part of the claim. The small dash broken line in FIGS. 2, 3, 4, 5, 7, and 9 depicts a portion of the repeater for wireless communications that

(Continued)

forms no part of the claim, while the large dash broken lines in FIG. 9 depict environmental structure that forms no part of the claim.

1 Claim, 6 Drawing Sheets
